PIPE WRAPPING MACHINE

James D. Cummings, Houston, Tex., assignor to
 Johns-Manville Corporation, New York, N. Y.,
 a corporation of New York

Application December 7, 1938, Serial No. 244,409

12 Claims. (Cl. 242—11)

This invention relates to a wrapping machine, and more particularly to a wrapping machine for applying a coating of protective material spirally about an object such as a pipe, while the same is in position in an extended pipe line or while in the form of a relatively short section.

It is an object of the present invention to provide a machine which can be advanced along a pipe line to apply a protective material thereto, or be maintained stationary and have sections of pipe passed through it to wrap protective material spirally about same.

It is another object of the present invention to provide a wrapping machine which is capable of applying a tight and smooth coating of wrapping material to a pipe or other object.

It is a further object of the present invention to provide a machine for wrapping protective material about a pipe, the machine being so constructed that the rate of application of the material to the pipe is automatically synchronized with the relative translational movement between the machine and the pipe or other object undergoing wrapping.

Other objects and advantages, if not specifically pointed out, will be apparent to those skilled in the art from the following detailed description of what are now considered the preferred embodiments of the present invention.

Referring to the drawings:

Fig. 1 is an elevational view of a machine constructed in accordance with the present invention and showing the machine in position on a pipe for applying a wrapping material to the same.

Fig. 2 is a fragmentary elevational view of a modification of the machine shown in Fig. 1, and

Fig. 3 is a horizontal sectional view taken substantially on the plane indicated by line 3—3 of Fig. 2.

The pipe wrapping machine comprises a frame 10 which may be formed of channel or other suitable sections welded or otherwise connected at their ends to form a substantially rectangular frame. The frame 10 may be given any suitable form, since it serves merely as a supporting structure for the other elements of the machine to be described later. A shaft 12 is journaled in depending brackets 14 which are riveted or otherwise connected to the frame 10. The shaft 12 carries traction wheels 16 which are fixed relatively to the shaft and are beveled on their opposite faces so as to make better contact with a pipe or other rounded body on which they

support the frame 10. A second shaft 18 is journaled in depending brackets 20, riveted or otherwise connected to the frame 10. Wheels 22, similar in all respects to the traction wheels 16, are affixed to the shaft 18. The pair of traction wheels 16, as well as the pair of wheels 22, may each be replaced by a single wheel suitably shaped to fit the curvature of the pipe or other rounded body if desired.

10 A power source 24, which may be any well-known type of internal combustion engine, an electric motor, or other prime mover, all of which are hereinafter designated by the term "motor," is suitably supported on frame 10. A sprocket 26 is affixed to the shaft 12 and is connected to a sprocket 28 carried by the engine 24 by a chain 30. Other types of motion transmission devices may be employed instead of the sprockets and chain if desired.

15 A plate 32 is suitably supported from the frame 10 as at 34 and is arranged to carry a series of rollers 36 which are positioned in the form of a circle. Plate 32 surrounds or partially surrounds the pipe to be wrapped and may well be in the form of an inverted U. In any case, an appreciable clearance is provided between the inner edge of the plate and pipe. A ring gear 38 of any suitable type is rotatably mounted on the rollers 36 which may be provided with 20 grooves to prevent the ring gear 38 from working off of their ends.

25 The ring gear 38 carries mountings for spools of wrapping material, the mountings being of any suitable type. Thus, for example, spool 30 mounting devices of the kind illustrated and described in detail in my co-pending application, Serial No. 238,951, filed November 5, 1938, may be employed. Alternatively, the spool mounting devices may be constructed as herein shown 40 and described and comprise oppositely positioned brackets 40, each of which is pivotally connected to a forked frame 42. Any well-known type of ball and socket connection may be used between each bracket 40 and frame 42 in place of a pivotal connection if desired. Each forked frame 42 45 rotatably supports a supply roll of suitable wrapping material 44. The ring 38, brackets 40, forked frames 42 and rolls of wrapping material 44 constitute a wrapping head which is rotatably supported on the frame in position to encircle a pipe by means of the rollers 36 and plate 32.

50 The ring 38 may be formed in two or more segments which are connected together by side plates 46 and bolt connectors 48.

The ring 38 is rotated by a pinion 50 carried by a shaft 52 rotatably supported on the frame 10 through the medium of journal bearings 54.

The end of the shaft 52 opposite to that which carries the pinion 50 is splined as shown at 56. A friction wheel 58 having a reduced shoulder provided with a groove 60 is connected to the shaft 52 for rotation therewith and movement therealong by means of a suitable key (not shown) which is mounted in the spline 56. The friction wheel 58 is driven by a second friction wheel 62 which has its axis substantially at right angles to the friction wheel 58 and is suitably affixed to one end of the shaft 18.

The speed of rotation of the shaft 52 relative to that of the shaft 18 may be varied by moving the friction wheel 58 radially of the friction wheel 62 to any desired adjusted position. A convenient means for effecting such an adjustment comprises a shaft 64 which is journaled in a lug 66 carried on the frame 10. The shaft 64 is prevented from axial movement by suitable collars 68 affixed thereto and is provided with a hand wheel 70 at one end and is threaded as shown at 72 at the other end. A nut 74 is threaded on the shaft and has a fork 76 connected thereto which is received within the groove 60 on the reduced shoulder of the friction wheel 58. Rotation of the hand wheel 70 causes the nut 74 to be threaded along the shaft 64 and through the medium of the fork 76 the friction wheel 58 is moved radially of the friction wheel 62.

In lieu of the change speed friction drive described above and illustrated in the drawings, other suitable means may be employed for driving the shaft 52 from the shaft 18 in any desired speed ratio. For example, a pinion and ring gear may be mounted on the shafts 52 and 18, respectively, the mounting being of any suitable type to permit the substitution of gears of different diameters.

A coating device C is carried by the frame 10, preferably between the wheels 22 and the plate 32. The coating device C may be of any conventional or suitable type and has been shown diagrammatically for this reason.

Suitable means are provided to counterbalance the weight of the coating and wrapping devices and also to ensure proper traction of wheels 16 on the pipe P. Such means may, for example, comprise weight W supported on the forward end of the machine.

A hand bar 75 is suitably connected as by means of a socket 77 to the frame 10. The hand bar enables the machine to be steadied by an operator walking alongside of the machine as it moves along a pipe. Alternatively, the bar 75 may be supported by a wheel or the like.

When it is desired to maintain the machine stationary and pass sections of pipe through it for wrapping instead of advancing the machine along an extended pipe line, the modification illustrated in Figs. 2 and 3 may be resorted to. In this modified form, the pipe wrapping machine previously described is provided with arms 78 which are suitably connected to the frame 10 and are provided with openings near their ends which receive standards 80. The standards 80 are connected with a base 82 by means of suitable sockets 84. The standards 80 may be formed of pipes and the sockets 84 may comprise pipe flanges. The standards 80 are provided with collars 86 which may be adjustably secured to the standards as by means of set-screws 88. Rollers

90, preferably similar to the wheels 16 and 22, are rotatably supported on the base 82 by means of uprights 92 and shafts 94. The rollers 90 are for the purpose of supporting the pipe P as it passes through the wrapping machine. The collars 86 are adjustably fastened in position on the standards 80 so that the full weight of the machine is borne by the pipe P as it passes through the machine, but so that the machine will not drop onto the base 82 when there is no pipe in the machine but will be caught by and supported on the collars 86.

Operation of the machine

The machine shown in Fig. 1 may be mounted upon a pipe line of indefinite length by removing the bolt connectors 48 and dropping the segment of the ring gear 38 which is in the lowermost position. To permit the mounting of the machine in this manner, the plate 32 is made of the inverted U-shape, previously referred to. If the coating device C is of the type which permits of segmental construction, it is preferably formed with a removable lower section which will be removed at this time in order for it to accommodate the pipe. After the machine is rested on the pipe, the lower section of the coating device is replaced and the lower segment of the ring 38 is replaced by replacing the side plates 46 and the bolt connectors 48 in well-known manner. Alternatively, particularly where the lower portion of the coating device is not susceptible of ready removal, an end of the pipe line may be threaded through the coating and wrapping devices in their assembled form.

The forked holders 42 for the supply rolls of the wrapping material 44 are adjusted angularly with relation to the axis of the pipe in accordance with the diameter of the pipe and the amount of overlap of the spirals desired. In the event that wrapping spool mountings are employed of the type disclosed in my said co-pending application, Serial No. 238,951, filed November 5, 1938, the spools may be adjusted on their mountings to obtain any desired arrangements of the wrappings as therein described. Coating material is placed within the coating device and the motor 24 is started. The motor 24 will, through the medium of the sprockets 26 and 28 and the chain 30, drive the traction wheels 16 and thereby propel the entire machine along the pipe line.

As the machine moves along the pipe line, the wheels 22 will, of course, be rotated, due to their frictional contact with the pipe line, and the friction wheel 62 will rotate the friction wheel 58 and drive the shaft 52 and the pinion 50 and thereby rotate the ring gear 38 around the pipe. Just prior to starting the machine, wrapping material is pulled from each supply roll 44 and fastened in any convenient way around the pipe. As the ring gear 38 rotates and the machine advances along the pipe, the wrapping material will be laid along the pipe in spirals which can be made to overlap to any extent desired by suitably adjusting the speed of rotation of the gear 38 relative to the speed of movement of the machine along the pipe by means of the hand wheel 70 which adjusts the position of the friction wheel 58 in the manner above described.

When relatively short pipe sections are to be wrapped, the machine is mounted, as illustrated in Fig. 2, on the stationary base 82 by resting the arms 78 on the collars 86 on the standards 80 as previously described. The motor 24 is then started and the pipe sections are passed through

the machine which wraps them in the same manner as when the machine moves on the pipe. During this type of operation, the motor 24 may be allowed to run continuously and the wrapping head will be automatically started and stopped as the pipe passes under and away from rollers 22, thereby dispensing with the necessity for a manually operated starting and stopping mechanism for the wrapping head.

Since the shaft 52 is driven from the shaft 18 which, in turn, is driven solely by the frictional contact of the wheels 22 with the pipe, the speed of rotation of the ring gear 38 and, concomitantly, the rate at which the wrapping material is applied to the pipe, is controlled solely by the rate of the movement of the machine relative to the pipe. It follows that variations in the speed of movement of the machine relative to the pipe, however great, will have no effect on the manner in which the wrapping material is applied around the pipe, because such variation will automatically produce similar variations in the rate of rotation of the ring gear 38. For this reason, a tight and smooth wrapping will always be applied to the pipe, regardless of the speed of movement of the machine relative to the pipe and irrespective of slippage which may occur between the traction wheels 16 and the pipe.

The present invention provides a machine which may be used to wrap either a long pipe line or a short pipe section with equal facility, and without requiring any extensive changes, and which will wrap a tight and smooth coating upon either one with a minimum of effort.

The foregoing details have been given for the purpose of explanation and not limitation, since many changes may be made in the embodiments described without departing from the scope of the invention which is to be limited only by the appended claims.

What I claim is:

1. A pipe wrapping machine comprising a frame, means for producing relative translational movement between the frame and a pipe or other object to be wrapped, means for applying wrapping material in spirals around said pipe, and means operated solely by said relative translational movement for driving said wrapping means.

2. A pipe wrapping machine comprising a frame, means for supporting said frame upon a pipe or other object to be wrapped, said means comprising a traction wheel, means comprising a motor in operative connection to said traction wheel for producing relative translational movement between the frame and pipe, means for applying wrapping material in spirals around said pipe, and means controlled by said relative translational movement for driving said wrapping means.

3. A pipe wrapping machine comprising a frame, wheels carried by said frame for supporting the same upon a pipe or other object to be wrapped, means for driving one of said wheels for producing relative movement between said frame and pipe, means for applying wrapping material spirally around said pipe, and means driven by another of said wheels rotated by contact with the pipe for operating said wrapping applying means.

4. A pipe wrapping machine comprising a frame, wheels carried by said frame and adapted to contact with a pipe or other object to be wrapped, means for driving one of said wheels

to produce relative translational movement between the pipe and frame, and means driven by another of said wheels rotated by contact with the pipe for applying wrapping material spirally around said pipe.

5. A pipe wrapping machine comprising wheels adapted to contact with a pipe or other object to be wrapped, a frame supported by said wheels, means for driving one of said wheels to produce relative translational movement between the pipe and frame, and means driven by another of said wheels rotated by contact with the pipe for applying wrapping material spirally around said pipe.

10 6. A pipe wrapping machine comprising a frame, wheels carried by said frame for supporting the same upon a pipe or other object to be wrapped, means carried by said frame for driving one of said wheels to propel the machine along the pipe, and means driven by another of said wheels rotated by contact with the pipe for applying wrapping material spirally around said pipe.

15 7. A pipe wrapping machine comprising a frame, wheels carried by said frame for supporting the same upon a pipe or other object to be wrapped, means carried by said frame for rotating one of said wheels to propel the machine along the pipe, means rotatable about said pipe for applying wrapping material to the same, and speed change means driven by another of said wheels rotated by contact with the pipe for rotating said wrapping applying means.

20 8. A pipe wrapping machine comprising a frame, wheels carried by said frame for supporting the same upon a pipe or other object to be wrapped, a motor carried by said frame, operative connections with said motor for rotating at least one of said wheels to propel the machine along the pipe, a wrapping head carried by said frame and rotatable about said pipe, a supply roll of wrapping material carried by said head, and speed change means driven by at least one other of said wheels as the latter is rotated through contact with the pipe for rotating said wrapping head.

25 9. A pipe wrapping machine comprising a frame, wheels carried by said frame for supporting the same upon a pipe or other object to be wrapped, means for driving one of said wheels to move the pipe axially, means for restraining said frame from translational movement, and means driven by another of said wheels as the latter is rotated through contact with said pipe for applying wrapping material spirally around the pipe.

30 10. A pipe wrapping machine comprising a frame, wheels carried by said frame for supporting the same upon a pipe or other object to be wrapped, means for driving at least one of said wheels to move the pipe axially, means for preventing movement of said frame axially of said pipe but allowing vertical movement thereof to permit the weight of the machine to be supported by the pipe, means for applying wrapping material around the pipe, and means driven by at least one other of said wheels as the latter is rotated through contact with the pipe to operate said wrapping material applying means.

35 11. A pipe wrapping machine comprising a roller support for a pipe or other object to be wrapped, a frame, wheels carried by said frame for supporting the same on the pipe, means for driving one of said wheels to advance said pipe axially, means for preventing movement of said

frame in a direction axially of said pipe but allowing vertical movement thereof to permit the weight of the frame and the elements carried thereby to be supported by the pipe, a wrapping head carried by said frame and rotatable around the pipe, means carried by said head for applying wrapping material to the pipe, and means for rotating said head driven by another of said wheels as the latter is rotated through contact with the pipe.

12. A pipe wrapping machine for traveling movement on an extended pipe, said machine comprising a frame, wheels carried by said frame for engagement with said pipe, means for

5 applying wrapping material in spirals around said pipe as said machine is advanced therealong, said means comprising a relatively narrow ring gear in the form of an annulus, a plurality of rollers supported from said frame and located interiorly of and carrying said ring gear, a mounting for a supply of wrapping material, said mounting being supported at one end by said ring gear and projecting from a face thereof and 10 including an unsupported outer end, and means driven by certain of said wheels during advancement of said machine for operating said wrapping means.

JAMES D. CUMMINGS.
